United States Patent

Des. 236,602
Patented Sept. 2, 1975

236,602

RAILWAY PASSENGER CAR BODY

Carl W. Sundberg, Bloomfield Hills, and Richard Heck,
West Bloomfield, Mich., assignors to Pullman Incorporated

Filed Oct. 1, 1973, Ser. No. 402,511

Term of patent 14 years

Int. Cl. D12—03

U.S. Cl. D12—37

FIG. 1.

FIG. 2.

FIG. 1 is a perspective view of a railway passenger car body showing our new design;

FIG. 2 is a front elevational view thereof;

FIG. 3 is a side elevational view thereof it being understood that the opposite side is a mirror image of the side shown herein; and

FIG. 4 is a top plan view thereof.

The broken lines in the drawing are for illustrative purposes only.

We claim:

The ornamental design for a railway passenger car body, substantially as shown and described.
